(57) **CLAIM**

The ornamental design for a stormwater inlet, as shown and described.

DESCRIPTION

FIG. 1 is a perspective view of the stormwater inlet as viewed from the back of the stormwater inlet.

FIG. 2 is a side elevational view of the stormwater inlet with the opposite side being a mirror image of the same.

FIG. 3 is a front elevational view of the stormwater inlet.

FIG. 4 is a top plan view of the stormwater inlet; and,
FIG. 5 is a rear elevational view of the stormwater inlet.
The broken lines shown in the drawings illustrate environment and portions of the stormwater inlet that form no part of the claimed design.
